PILE FABRIC AND METHOD OF WEAVING

Thomas T. Janney, Lafayette Hills, Pa., assignor to James Lees and Sons Company, Bridgeport, Pa., a corporation of Pennsylvania

Application March 14, 1957, Serial No. 645,989

7 Claims. (Cl. 139—404)

This invention relates to an improved pile fabric and more particularly to a Wilton-type carpet having superior wear and strength features.

In order to achieve better stability in the ground fabric of a floor covering and at the same time to conserve the amount of face yarn used, it is desirable to weave some of the face yarn through to the back in a multi-shot Wilton-type fabric. Where a conventional two-shot construction is used having upper and lower planes of filling shots bound together by chain warps and a plurality of stuffer warps carried between the shots, it is well known to weave the face yarn under some or all of the upper shots. This construction does have, however, some disadvantage from a quality standpoint in that the pile material is not bound as firmly as in other constructions and, also, the weight and stiffness of the ground fabric is not all that might be desired. However, in carrying all or substantially all of the face yarn through to the back or running dead along with the stuffer, there is a very substantial increase in cost because of the amount of relatively expensive yarn that is used.

Contrary to conventional practice, I weave the ground fabric of the present invention with two succeeding filling shots over the stuffer and the next succeeding two filling shots under the stuffer or vice versa. The stuffers are tensioned sufficiently so that they are relatively straight in the ground fabric, whereas each filling weft is woven under and over the stuffer and pile warps. In the preferred form, a single chain warp is shown since this suffices to anchor the filling and the stuffer. The pile warps may be carried over a plurality of wefts and pile wires, through to the back between the wire and a weft, or they may run dead with the stuffer warps.

A primary object of the invention then is to provide a two-shot, Wilton-type fabric in which each weft shot passes above and below the stuffer warps.

A further object of the invention is to provide a Wilton-type fabric in which the weft shots pass in pairs above and below the stuffer warps.

A further object of the invention is to provide in a two-shot, Wilton-type fabric having a pair of adjacent weft shots on the same side of the stuffer, pile warps carried through to the back under single bottom shots of pairs, tied in under single top shots of pairs, tied in under a single bottom shot, over the next bottom shot, under the next top shot and the succeeding top shot.

A still further object is to provide in a fabric of the type described, a pile yarn carried through to the back and tied in under a single bottom shot, then over the next bottom shot and under its associated pile wire, then over the next pile wire.

Further objects will be apparent from the specification and drawings in which—

Fig. 1 is a top view diagrammatically illustrating a fabric of the present invention,

Fig. 2 is a section as seen at 2—2 of Fig. 1,

Fig. 3 is a section as seen at 3—3 of Fig. 1,

Fig. 4 is a section as seen at 4—4 of Fig. 1, and

Figs. 5—7 show various draws used to produce fabrics of the invention.

The invention comprises primarily the weaving of a ground fabric having pile warps in which the stuffer is held in the same shed position for two shots before it is reversed for the succeeding two shots. The pile yarn, however, is carried so that the several yarns in a dent may be over, under, or between single shots regardless of whether they are above or below the stuffer.

Referring now more particularly to the drawings, the present fabric in its preferred form has pairs of weft or filling shots 10a, 10b, 11a, 11b, etc., through 17a, 17b. The filling shots interweave with the stuffer warps but the individual shots are preferably separated by pile yarns. Stuffer warps 20, 20 are interwoven with pairs of shots 10—17. Chain warps 21, 21 pass successively under and over pairs of shots. Contrary to usual practice, the terminology "top and bottom shots" cannot be strictly applied to the various filling wefts because each weft weaves from top to bottom, so that in Fig. 2 certain pairs of wefts appear as bottom shots whereas the same wefts appear as top shots in Fig. 3. The position of the shots in the sectional views is clearly designated in the tables herein-after. Preferably I utilize two pile warps 22 and 23 in each dent and these warps may be individually or jointly carried over, under, and between individual as well as pairs of weft shots in a manner which provides novel design effects.

The weave diagrams of Figs. 2—4 show diagrammatically sections of the fabric before the pile wires 25—32 have been withdrawn. These wires may be any selected combination of high and low round wires, profile wires, and cutting wires. The following tables may be used to trace the relative relation of the two pile warps in dents A and B as seen in Fig. 1 and Figs. 2 and 3.

Dent A (Fig. 2)

35	Shot	Position of Shot	Yarn 22	Yarn 23
40	10a	Top	Under	Under
	10b	do	Over shot and wire 25	Over shot, under wire 25
	11a	Bottom	Under	Under
	11b	do	Over shot and wire 26	Over shot, under wire 26
	12a	Top	High float	Under
	12b	do	Over shot and wire 27	Over shot, under wire 27
45	13a	Bottom	Under	Under
	13b	do	Over shot, under wire 28	Over shot and wire 28
	14a	Top	Intermediate float	Under
	14b	do	Over shot and wire 29	Over shot, under wire 29
	15a	Bottom	Under	Under
	15b	do	Over shot and wire 30	Over shot, under wire 30
50	16a	Top	Under	Under
	16b	do	Over shot and wire 31	Over shot, under wire 31
	17a	Bottom	Under	Under
	17b	do	Over shot and wire 32	Over shot, under wire 32

Dent B (Fig. 3)

55	Shot	Position of Shot	Yarn 22	Yarn 23
60	10a	Bottom	Under	Under
	10b	do	Over shot, under wire 25	Over shot and wire 25
	11a	Top	Under	Under
	11b	do	Over shot and wire 26	Over shot and wire 26
	12a	Bottom	Under	High float
	12b	do	Over shot and wire 27	Over shot and wire 27
65	13a	Top	Intermediate float	Under
	13b	do	Over shot, under wire 28	Over shot and wire 28
	14a	Bottom	Under	Under
	14b	do	Over shot and wire 29	Over shot, under wire 29
	15a	Top	Under	Under
	15b	do	Over shot, under wire 30	Over shot and wire 30
70	16a	Bottom	Under	Under
	16b	do	Over shot, under wire 31	Over shot and wire 31
	17a	Top	Under	Under
	17b	do	Over shot and wire 32	Over shot, under wire 32

This weaving provides a very unusual and interesting combination of loops and ground pile fabric which has a definite ground coverage and selective high and intermediate pile areas in accordance with the cutting of the jacquard cards. Accordingly, a high float such as shown at F in Figs. 2 and 3 may be aligned weftwise in the fabric with a lower pile area in the same dent or with pile loops individually carried over each wire but bound into the fabric as preferably shown at G in Fig. 3. An intermediate float H can be made by carrying one of the pile yarns from a through-to-the-back condition such as shown in Fig. 2 under weft shot 13a, thence over the next shot 13b, under the associated wire 28, and directly over the next wire 29.

Another variation of an intermediate float is shown at J, Fig. 3, in which pile yarn 22 is carried over wire 27, over shot 13a, over shot 13b, under wire 28, and then through to the back to be tied in under shot 14a. The inherent nature of the weave of the present invention illustrates the difference between the intermediate floats H and J, because in float H the yarn 22 is carried over wire 29 which is associated with shot 14b in top position, and the float H is tied in under shot 13a in bottom position. Furthermore, the float passes over shot 14a in top position and shot 13b in bottom position. Compare this with float J in which the wire 27 forming the float is associated with shot 12b in bottom position and the float is carried to the first next succeeding bottom weft 14a rather than the second one 14b.

The draw for the fabric shown in Figs. 1-4 is shown schematically in Fig. 5, in which the chain for dent C is controlled by harness 35, the stuffer for dent C and the chain for dent D, which is adjacent to it, are controlled by harness 36 and stuffer for dent C is carried through harness 35. The repeat is indicated at 37. It will thus be apparent that the chains and the stuffers in adjacent dents work oppositely.

Fig. 6 illustrates the same basic draw but with a longer repeat 39. In this variation the draw in dents E and F is identical, with the chains on harness 35 and the stuffer for each dent on harness 36. However, the draw for dents G and H is the reverse with the stuffers on harness 35 and the chains on harness 36. A narrower repeat 40 is shown in Fig. 7 in which all the stuffers work in harness 35 and all the chains in harness 36 so that when the stuffer warps are up all chain warps are down and the cross section of each dent would be the same.

It is, therefore, possible to provide different types of intermediate floats in the same weave depending upon which position of the particular weft shot is selected to tie under and whether the wire forming the float is asso-

ciated with the first or second pair of shots in top or bottom position. Similarly, individual variations in all the other formations are possible, thus creating an extremely wide range of texture effects available to the designer.

Having thus described my invention, I claim:

1. A Wilton type pile fabric having stuffer warps, a plurality of weft shots interwoven with said stuffer warps, a chain warp binding the weft shots, a plurality of pile warps tied under weft shots both above and below the stuffer warps, the same weft shots binding down pile warps on the top and on the bottom of the fabric.

2. A fabric in accordance with claim 1 in which the weft shots interweave in pairs with the stuffer warps.

3. A fabric in accordance with claim 1 in which pairs of stuffer warps interweave with pairs of weft shots.

4. A fabric in accordance with claim 1 in which the pile warps interweave in pairs with the weft shots.

5. A pile carpet fabric having pairs of relatively straight stuffer warps, pairs of weft shots interweaving with said stuffer warps which pass alternately over the top and under the bottom of the stuffer warps, chain warps for binding the weft shots a pile yarn between pairs of stuffer warps said pile yarn tied down under one weft shot on the bottom of the fabric and under another weft shot on the top of the stuffer warp and passing over at least one intermediate weft shot.

6. In the manufacture of pile fabrics having pile warps, stuffer warps, chain warps, and filling wefts, the method which comprises the steps of interweaving pairs of filling wefts and stuffer warps, weaving selected pile warps over at least two pile wires and associated filling wefts, and tying in said pile warps under a single weft shot of a pair on the bottom of the fabric.

7. In the manufacture of pile fabrics having pile warps, stuffer warps, chain warps, and filling wefts, the method which comprises the steps of interweaving pairs of filling wefts with stuffer warps, weaving selected pile warps between single wefts of pairs of weft shots, and under an associated pile wire.
